UNITED STATES PATENT OFFICE

BROR ANDERS EMIL JOHNSON AND GUSTAF ÖRSTRÖM, OF ALSTEN, SWEDEN, ASSIGNEES
TO AKTIEBOLAGET GERH. AREHNS MEKANISKA VERKSTAD, OF STOCKHOLM,
SWEDEN, A CORPORATION OF SWEDEN

MEANS FOR ARRANGING OVAL CIGARETTES

Application filed May 6, 1931, Serial No. 535,518, and in Germany May 9, 1930.

In the packing of oval cigarettes and similar staff-shaped articles in boxes the cigarettes generally are so placed, that they incline in the same direction and consequently 5 partially cover one another. Owing to this arrangement the cigarettes require smaller space and the packages become neat. The present invention relates to a device in machines for packing oval cigarettes and similar staff-shaped articles, by means of which 10 the cigarettes of a group to be introduced into the box, are subjected to such a correction regarding their inclined position that they will be placed in the box in the right position. The main features of the device consist therein that the cigarettes of the said group are placed in chambers or partitions, one in each chamber, the width of which is so adapted that the cigarettes are compelled 15 to occupy an inclined position in the chamber and consequently can not be turned round but be caused to change its inclined position in one direction to an inclined position in opposite direction through the actuation of 20 one or more members, between which and the chambers a relative movement is effected.

Fig. 1 in the accompanying drawings shows diagrammatically and in a front view a form of execution of the invention. Fig. 2 is a 25 cross-section on the line A—B in Fig. 1. Figs. 3 and 4 show two other forms of execution of the invention. Figs. 5 and 6 are an end view and a plan view respectively of the device shown in Fig. 4.

The cigarettes *a*, Fig. 1, are placed in a magazine 1 from which they descend into partitions 2, effected by means of plates 3. A slide 5 is movable on a bar 4 located in the front of the partitions 2, the said slide being 30 provided on its top side with chambers 7, effected for instance by means of strips 6 of sheet metal mounted in the slide. In one position of the slide the said chambers are located opposite to the partitions 2, so that 35 the lowermost row of cigarettes may be transferred to the chambers of the slide by means of a piston 8 divided into fingers, while the next superposed cigarettes in the partitions are retained by a bar 9. Slide 5 is reciprocated on the bar 4 by a lever arm 10, which is

acted upon by a spring 25 and a cam disc 26 on the driving shaft 27 of the machine and is connected to the slide by a link 11. The bar 4 is provided with flanges 12 on its top-side. The bottom of the chambers 6 is located somewhat below the top-side of the said flanges, so that the cigarettes located in the chambers rest upon the flanges, as perceived from Fig. 2. The said flanges are wave-shaped for a part of their length. The width of the partitions 55 2 and the chambers 7 is so adapted, that the cigarettes are compelled to occupy an inclined position. For that reason the cigarettes in the chambers 7 can not be turned round but their inclined position may be 60 changed. While the slide is moved toward the right, Fig. 1, the cigarettes in the chambers 7 are subjected to a resistance effected by wave-shaped projections of the flanges 12, which results in the cigarettes, inclining toward the left being caused to occupy an inclined position toward the right, while cigarettes which already incline toward the right remain in this position, so that, consequently, 65 all cigarettes of the group occupy the same 70 inclined position at the end of the movement of the slide. In order to accelerate the correction of the position of the cigarettes, the bar 4 may be slidably mounted and moved toward the left, while the slide is moved toward 75 the right. The corrected cigarettes are moved by a piston preferably into a compressor chamber, in which the cigarettes are forced toward each other to a compact row which then is transferred into the box. 80

In the form of execution of the invention shown in Fig. 3 a belt 13, ribbon or the like is substituted for the bar 4, said belt passing around rollers 12. The slide 14 provided with the chambers 15 is movable in a guide 85 (not shown) and the cigarettes contained by the chambers rest upon the top part of the belt 13.

After the cigarettes have been transferred from the partitions 16 into the chambers 15, 90 the slide 14 is moved toward the right. At the same time the belt 13 is run in the direction indicated by the arrow. During this operation the same turning of the cigarettes is effected as in the device shown in Figs. 100

1 and 2, so that all cigarettes of the group will incline toward the right, as illustrated by dotted lines. Owing to the fact that the slide and the support for the cigarettes 5 are moved in opposite directions, the correction of the position of the cigarettes is effected very rapidly, so that it is not necessary to move the slide through any longer distance for the effecting of the correction. The cigarettes, evidently, will be turned into the same direction even if the slide is stationary and only the belt is moved. The transferring of the cigarettes from the chambers into the compressor chamber may then be effected 15 by the same piston which moved the cigarettes from the distribution partitions 16 into the chambers 15.

According to the form of execution shown in Figs. 4 to 6 inclusive the turning of the 20 cigarettes is effected by two belts 19 and 20, ribbons or the like passing round rollers 17 and 18 respectively. The cigarettes are transferred by a piston 21 from the distribution partitions 22 to chambers 23, provided 25 on a stationary table 24, in which a slot for the upper part of the belt 20 is made, by which the cigarettes in the chambers are supported. The lower part of the belt 19 bears against the top side of the cigarettes.

30 After the cigarettes have been transferred from the distribution partitions 22 to the chambers 23 and the belts 19 and 20 are put into motion, both belts, evidently, effect a turning action on the cigarettes inclined 35 toward the left, so that these cigarettes are compelled to occupy the same inclined position as the other cigarettes. Also in this case a rapid turning of the cigarettes is effected, which then may be ejected from the chambers 40 23.

The invention may, evidently be carried out in many other ways than the above stated only as examples.

We claim:

45 1. In a machine for packing oval cigarettes and similar staff-shaped articles a device for bringing the cigarettes into the same inclined position before their introducing into a box or the like, said device comprising a number 50 of chambers each adapted to contain only one cigarette and so arranged, that the cigarette may not be turned round in the chamber but only occupy one or the other of two symmetrical inclined positions in the same, and 55 a member in contact with the cigarettes, so that at a relative movement between the chamber and the said member transversely of the cigarette the cigarette is brought into a distinct inclined position.

60 2. In a machine for packing oval cigarettes and similar staff-shaped articles a device for bringing the cigarettes into the same inclined position before their introducing into a box or the like, said device comprising a number 65 of chambers, which are open at their upper

side and to their full breadth and each are adapted to contain only one cigarette, the said chambers being so arranged that the cigarette may not be turned round in the chamber but only occupy one or the other of two symmetrical inclined positions in the same and a member in contact with the lower side of the cigarette, so that at a relative movement between chamber and the said member transversely of the cigarette the cigarette is 75 brought into a distinct inclined position.

3. A form of execution of the device stated in claim 1 characterized by the fact that the chambers are located on a member, sustaining the cigarettes in the chambers by a friction surface, the said chambers and member being movable relatively to one another transversely of the chambers.

4. A form of execution of the device stated in claim 1 characterized by the fact that the chambers are located on a member sustaining the cigarettes in the chambers during the turning operation by ribs extending longitudinally of the member, the said chambers and member being movable relatively to one another transversely of the chambers.

In testimony whereof we have hereunto affixed our signatures.

BROR ANDERS EMIL JOHNSON.

GUSTAF ÖRSTRÖM.
